UNITED STATES PATENT OFFICE.

EVA C. HAMILTON, OF HUBBARD, OREGON.

DESIGN FOR A DOLL.

49,993.

Specification for Design.

Patented Dec. 5, 1916.

Application filed October 9, 1916. Serial No. 124,734. Term of patent 3½ years.

To all whom it may concern:

Be it known that I, EVA C. HAMILTON, a citizen of the United States, and resident of Hubbard, in the county of Marion and State of Oregon, have invented a new, original, and ornamental Design for a Doll, of which the following is a specification, reference being had to the accompanying drawing, forming part thereof.

Figure 1 shows a front view of a doll embodying my invention. Fig. 2 shows a side view of the same, and Fig. 3 shows a back view of the same.

I claim:

The ornamental design for a doll, as shown.

Des Moines, Iowa, September 5, 1916.

EVA C. HAMILTON.
